UNITED STATES PATENT OFFICE

172,065

ELECTRIC SOAP DISPENSER

Arthur M. Thiel, St. Louis, Mo.

Application July 16, 1953, Serial No. 26,005

Term of patent 14 years

(Cl. D4—3)

To all whom it may concern:

Be it known that I, Arthur M. Thiel, have invented a new, original, and ornamental Design for an Electric Soap Dispenser, of which the following is a specification, reference being had to the accompanying drawing, forming a part hereof.

Figure 1 is a plan view of the electric soap dispenser, showing my new design;

Figure 2 is a view in front elevation of the electric soap dispenser;

Figure 3 is a view in side elevation of the device shown in Figures 1 and 2; and

Figure 4 is a view in perspective of the device shown in Figures 1 through 3.

I claim:

The ornamental design for an electric soap dispenser, as shown.
